UNITED STATES PATENT OFFICE

JOHAN A. ANDERSON, OF CRANSTON, RHODE ISLAND, ASSIGNOR TO UNIVERSAL WINDING COMPANY, OF BOSTON, MASSACHUSETTS, A CORPORATION OF MASSACHUSETTS

WINDING MACHINE

Application filed September 21, 1927. Serial No. 221,072.

This invention relates to improvements in winding machines for winding cops, cones or packages of yarn, thread and other strand material, and particularly to drum-winding machines in which the cop or package is rotated through peripheral contact with a drive-roll or drum.

The present invention is directed to the means for controlling the movement of the cop- or cone-holder away from the driving-drum as the cop or package increases in diameter and to the stopping-mechanism for automatically arresting the winding operation when the cop or package reaches a predetermined size.

The present improvements relate to the type of controlling- and stopping-mechanism shown and described in U. S. Letters Patent, No. 1,656,088; dated January 10, 1928.

The particular object of the present improvements is to increase the efficiency and reliability of the controlling- and stopping-mechanism disclosed in the prior application above referred to.

Further objects of the improvement are set forth in the following specification which describes a preferred embodiment of the invention as illustrated by the accompanying drawings. In the drawings:

Fig. 1 is a side elevation of one unit of a cone-winding machine illustrating the improved controlling-means and stopping-mechanism as applied to use thereon;

Fig. 2 is a detailed side view of the controlling-means and stopping-mechanism of the machine showing the parts in the relation they assume when the winding operation is arrested.

Fig. 3 is a fragmentary view of the same illustrating the method of operation of the stopping-mechanism of the machine;

Fig. 4 is a side view similar to Fig. 2 illustrating the method of resetting the stopping-mechanism to start the operation of the machine;

Fig. 5 is a detailed side view of the ratchet cop-lifting device of the stopping-mechanism;

Fig. 6 is a detailed view of this part of the device shown from the opposite side;

Fig. 7 is a detailed edge view of the dogging-device;

Fig. 8 is a detailed plan view of the detent-means for normally maintaining the stopping-mechanism inactive;

Fig. 9 is a detailed side view of the dogging- or controlling-mechanism for regulating the movement of the cop- or cone-holder away from the drive-roll during the winding of the package.

The machine in general is substantially the same in construction and arrangement as that disclosed in the prior patent above referred to. Referring first to Fig. 1 of the drawings, 2 designates the rotating drive-roll or friction-drum from which the cop or package is driven; 3 the rotating cop-holder or mandrel on which the cop is wound, in the present instance illustrated in the form of a cone-holder; 4 the reciprocating thread-guide which traverses the strand of yarn or thread longitudinally of the cop-holder to deposit it in helical coils thereon; and 5 the rotating cam which reciprocates the thread-guide 4.

The drive-roll 2 is mounted on a rotating shaft 7 which is driven continuously from suitable power means not herein shown. Usually, the power-shaft 7 is continuous for receiving a plurality of drive-rolls arranged at intervals along the machine frame which carries a number of winding units or heads. In the present embodiment the cone-holder 3 is rotatably mounted on a bearing 8 which is swiveled at 9 on the end of a curved arm 10. The arm 10 is hinged on a pivot-stud 11 held in a bracket 12 mounted on the machine frame-member 6, whereby to support the cone-holder 3 in position to bear against the drive-roll 2 and to adapt it to swing upwardly therefrom in an arcuate path as the cone or package is built up on the holder. The cone-holder 3 is adapted to tilt on its swiveled bearing 9 as it moves upwardly away from the drive-roll 2 to regulate the taper on the periphery of the cone being wound, the mechanism for controlling this action being illustrated in general at 13 as

embodying the construction shown and described in U. S. Letters Patent, No. 1,658,400, dated February 7, 1928.

The thread-guide 4 is mounted at the front of the drive-roll 2 to adapt it to reciprocate longitudinally thereof. As shown in Fig. 2 the thread-guide 4 projects upwardly from a slide 14 which is slideable on a horizontal bar or rod 15. A second horizontal bar 16 is engaged by a hooked bearing 17 on the back of the guide 4 to maintain the latter in erect position as it slides on the rod 15. The rod 15 and bar 16 are secured in place at the front of the machine by means of suitable bearing-blocks 18, see Fig. 1, which clamp them against the vertical arms 19 forming a part of the frame-members 6. The slide 14 is provided with a lug 22 through which extends a stud 23 carrying a bowl or roller 24 at its lower end which engages with the helical groove 25 in the cam 5. The cam 5 is carried on a continuously rotating shaft 27 which extends throughout the length of the machine frame to operate the cams for other winding units mounted thereon. The rotation of the cam 5 causes the guide 4 to reciprocate back and forth at the front of the drive-roll 2, and the upper end of the guide 30 is inclined inwardly toward the point of contact of the cop with the periphery of the drive-roll and provided with a suitable thread-groove 28 through which the strand γ leads to direct it onto the cop. The above described instrumentalities constitute the essential elements of the winding mechanism of the machine and are similar in general construction and arrangement to those heretofore employed in the art.

It has been noted that as the cop or cone builds up on the holder 3 the latter swings upwardly with its supporting arm 10, and suitable dogging-means are usually provided for steadyng the motion of the cone-holder and preventing a retrogressive movement thereof. In the present invention the dogging-means comprise an improved construction over that described and illustrated in the prior application first referred to. As in the prior invention, the dogging-means is adapted to cooperate with the stopping-mechanism of the machine to arrest the winding operation, but in a somewhat different manner. In the previously shown construction the dogging-mechanism comprises an arcuate slide or quadrant 30 which depends from the swinging arm 10. Referring to Fig. 1, the quadrant 30 is held in an arcuate slot 31 on the side of the arm 10 and is clamped in position by means of a bolt 32 and washer 33 overlying its side. Through this arrangement the quadrant 30, which is employed as a slideable element for actuating the stopping-mechanism, may be adjusted in the slot to regu-

late the extent to which it projects below the arm 10, this adjustment providing for setting the quadrant to trip the stopping-mechanism when the arm 10 has been moved upwardly to a predetermined extent in accordance with the diameter of the cop or package to be wound. This same arrangement of the quadrant 30 is employed in the present construction.

The dogging-means which cooperate with the quadrant 30 to act frictionally thereon to prevent retrogressive movement of the arm 10 comprises the previously disclosed sliding rod or bar 35 which also forms the tripping-means or trigger for the stopping-mechanism. As shown in Figs. 1 and 2, the slide or bar 35 is mounted to slide through a slotted bearing 36 formed on an arm or extension 37 of the bracket 12. The slide or bar 35 is provided with two longitudinal slots 38 which are engaged by pins 39 and 40 to hold the slide in suspension; the rearward pin 39 being driven through the sides of the slotted bearing 36 and the forward pin 40 projecting from the side of the bearing-block 18 previously described as fastened to the arm 19 of the frame-member 6. Instead of arranging the slide 35 to bear directly on the quadrant 30 to effect the dogging-action, as in the device of the prior application first referred to, in the present invention the dogging-means is constituted as a separate element connected to be operated from the slide. As shown in Figs. 1, 5 and 8, the extension 37 of the bracket or frame-member 12 has an arm 41 extending upwardly therefrom and carrying a pin 42 fast in its upper end. Pivoted to rock on the pin 42 is a bifurcated dogging-element or lever 43, shown in detail in Fig. 7, arranged with its opposite arms 44 straddling the sides of the quadrant 30, see Figs. 5 and 8. The lower end of the dogging-member 43 is offset slightly to abut the side of the slide 35 and is provided with a lip 34 at the bottom adapted to engage a slot 26 on the under side of the slide. The two arms 44 of the dog 43 are connected by a cross-strip 29 having its edge beveled to adapt it to act as a shoe engaging against the convex face of the quadrant 30 as shown in the detailed view, Fig. 9. Through this arrangement the fixed pin 42 engages one side of the quadrant and the cross-strip or shoe 29 bears against the opposite side so that when the dog is rocked on the pin 42 it will exert a frictional binding action on the quadrant to resist the downward sliding movement of the latter. This action prevents retrogressive movement of the cop-holder after the latter has been forced upwardly by the growth in the winding.

The dog 43 is rocked to effect the frictional gripping action through the sliding movement of the slide 35 connected to its

lower end by means of the lip 34 and slot 26, the slide being under the influence of resilient means such as the spring 45. The spring 45 surrounds the slide 35 and is held against the rearward side of the bearing 36 with its opposite end pressing against a pin 46 driven through the slide. The spring 45 thus acts to adjust the slide rearwardly with respect to the front of the machine to rock or tilt the dog 43 to press the beveled face of its shoe 29 against the convex face of the quadrant 30. The dog thus acts both to resist the upward swinging movement of the arm 10 carrying the cop-holder 3 and to more positively check retrogressive movement of the arm in the manner as before explained. The movement of the cone- or cop-holder 3 away from the drive-roll 2 is thus more efficiently controlled to provide a smooth, vibrationless motion whereby the cop or cone is prevented from jumping or rebounding with respect to the drive-roll during the winding operation.

It has been stated that the slide 35 acts as the trip for the stopping-mechanism of the machine, the engaging portion or shoe 29 of the dog 43 being adapted to slide off from the end of the quadrant 30 after the package has reached a predetermined diameter in accordance with the adjustment of the quadrant on the arm 10. The instrumentalities which cooperate with the slide 35 to arrest the winding operation are illustrated in detail in Figs. 2 to 4 and will be next explained. To arrest the rotation of the cop- or cone-holder 3 the arm 10 is lifted to remove the package from contact with the drive-roll 2 as is the usual practice in machines of the present type. The lifting of the cone-holder 3 is accomplished by positively raising the arm 10 through the means of a ratchet-mechanism, shown in detail in Figs. 5 and 6, which acts on the quadrant 30. It will be noted from these views that the quadrant 30 is formed with ratchet teeth 49 on its rearward side as viewed in Figs. 2 and 4. Adapted to engage the teeth 49 on the quadrant 30 is a pawl 50 which is pivoted at 51 to a swinging lever 52, see Fig. 6. The pawl 50 has a tail-piece 53 acted upon by a plunger 54 which is under the pressure of a spring 55 held in a pocket depending from the lever 52. The spring 55 maintains the pawl 50 in engagement with the teeth 49 and, preferably, the bearing of the pawl on its pivot 51 is made more or less loose to provide play so that the pawl may adjust itself to the teeth when the quadrant 30 is moved a distance less than the length of a tooth.

The lever 52 is fixedly secured to the end of a rod 56 which is rockably mounted in a bearing 57 forming a part of the arm 37 on the frame-member 6 as shown in Fig. 2. The rod 56 has a second bearing 48 at the

front of the frame-member 6 as shown in Fig. 1. The rod 56 also forms the lock or detent for maintaining the stopping-mechanism normally inactive, its forward end being bent into a crook at 58 and terminating in an inclined arm 59 formed with a pointed detent-blade 60, see Fig. 8. The detent-blade 60 is adapted to engage a notch or shoulder 61 on a latch-plate 62 which is fastened to the top of a post 63 projecting upwardly from a rockable member 65, shown in Fig. 2 and later described. The latch-plate 62 is adapted to be rocked into the position shown by dotted lines in Fig. 8, whereby the detent-blade 60 is released from the shoulder 61 to cause it to slide along the inclined edge 64 of the plate 62 in the manner and for the purpose as hereinafter explained. The release of the detent-blade 60 permits the rod 56 to be rocked under the influence of a spring 67 which is anchored to the frame-member 6, see Fig. 1, with its upper end engaging the hooked end 68 of an arm 69 on the lever 52, see also Fig. 6. A stop-screw 70 screwed through the arm 69 and locked in place by a checknut 71 is adapted to strike against the top of the arm 37, see Figs. 1 and 5, to limit the rocking-motion of the lever 52 under the action of the spring 67. When the detent-rod 56 is released the spring 67 will rock the lever 52 carried thereon to lift the pawl 50 to a certain extent as regulated by the adjustment of the stop-screw 70. The lifting of the pawl 50 in this manner acts through the ratchet on the quadrant 30 to slide the latter upwardly whereby to raise the arm 10 to lift the package, indicated at Y in Fig. 2, out of contact with the drive-roll 2 to arrest the winding operation. It will thus be apparent that the lever 52, the pawl 50 and the spring 67 constitute the means hereinafter referred to as the stopping mechanism for arresting the operation of the machine.

It has been noted that the thread-guide 4 is reciprocated continuously and therefore as the cop or cone is lifted away from the drive-roll 2 to arrest the winding operation it is desirable that the strand y be removed from the guide to prevent the yarn or thread from being cut or broken. The rockable member 65, previously described as carrying the latch-plate 62, constitutes the thread-lifter for disengaging the strand y from the thread-guide 4. As shown in Figs. 2 and 4, the thread-lifter 65 is constructed in the form of a relatively flat plate provided with suitable trunnion bearings 75 on the main frame of the machine. Referring to Fig. 4, the thread-lifter 65 normally assumes a position with its upper edge at the rear of and below the guiding-groove 28 in the thread-guide 4, being retained in this position by the engagement of the latch-

plate 62 with the detent-blade 60 on the rockable rod 56. The thread-lifter 65 is rocked into the position shown in Fig. 2 to release the detent-rod 56 and to act concurrently to lift the strand *y* out of the groove in the thread-guide 4 in the manner as later explained. This action of the thread-lifter is effected through the cooperation of instrumentalities as next described.

Referring to Figs. 2, 3 and 4, a bifurcated lever 77 is pivoted to the pin 40 which supports the forward end of the slide 35, the opposite legs of the lever being straddled across the slide. The lever 77 has an elbow-shaped arm 78 which is formed with an inclined slot 79 engaged by a pin 80 projecting from the side of the slide 35. When the slide 35 is slid into the position shown in Fig. 3, under the pressure of the spring 45, the pin 80 slides in the slot 79 to tilt the elbow-shaped arm 78 of the lever 77 upwardly. The end of the arm 78 of the lever 77 is hooked under a crank-arm 81 which, as shown in Fig. 2, forms part of a wire rod 82 pivotally mounted in lugs 83 on the under side of the thread-lifter 65. The crank-arm 81 has a hook 84 at its end to which is connected a wire link 85. The link 85 is hooked beneath the tail-piece 86 of a knockoff lever 87 which is pivoted on a pin 89 projecting from the side of a lever 90. The lever 87 has a bifurcated portion 88, the sides of which straddle the lever 90. The lever 90 is pivoted on a pin 91 driven into the side of the frame-member 6 and its upper end is bent over at 92 to adapt it to engage a tail-piece 93 projecting at an angle from one of the bearings of the thread-lifter 65. The tail-piece 86 on the lever 87 projects into position to adapt its end to be engaged by a going element of the machine, such as the toothed collar or wheel 95 which is secured to the cam-shaft 27 to rotate therewith. A pin 96 projecting from the side of the machine frame limits the upward movement of the tail-piece 86 of the lever 87 whereby when the end of the tail-piece is engaged by a tooth on the wheel 95 the lever will be moved bodily to rock the connected lever 90 in the direction indicated by the arrow in Fig. 3. This rocking action of the lever 90 brings its bent portion 92 against the tail-piece 93 on the thread-lifter 65 to rock the latter to raise the thread out of the thread-guide while releasing the detent for the stopping-mechanism in the manner as herein-after more fully explained.

The lever 87 may also be rocked to engage its tail-piece 86 with the toothed wheel 95 to arrest the winding operation when the strand breaks, a suitable breakage-lever 125 shown in Fig. 4 being employed for this purpose. The breakage-lever 125 extends outwardly from the rod 82 and is adapted to rock said rod when released from the

strand *y*. The lever 125 acts in the manner explained in the previous application to raise the arm 81 to cause it to act through the link 85 to lift the tail-piece 86 of the lever 87 into position to be engaged by the rotating collar or wheel 95 in the manner as shown in Fig. 3.

Referring now to Figs. 2, 4 and 8, the detent-rod 56 carries a lever 128 having its hub abutting the side of the bearing 57 and secured fast to the rod by means of a binder-screw 129. The lever 128 has a bevel-sided lug 130 at its lever end which is adapted to co-act with the inclined side of an upright arm or cam-plate 131 fastened to the slide 35. As shown more particularly in Fig. 8, the cam-plate 131 is riveted to the rearward side of the bar slide 35 at 132 with its arm reaching upwardly therefrom and outwardly in front of the rockable rod 56. At its upper end the arm is extended in a narrow portion or finger 133 adapted to bear against the side of the rod 56 to take the thrust of the cam-plate 131 when the latter is acted upon by the lever 128. As shown in Fig. 8, the cam-plate 131 is bent to form the inclined face 134 against which the beveled lug 130 engages when the lever 128 is rocked with the rod 56. The lever 128 will thus effect a prying action on the cam-plate 131 to slide the slide 35 to the left as viewed in Fig. 2 against the action of its spring 45. The purpose of this arrangement, which is a feature of improvement over the mechanism described and illustrated in the patent first referred to, is to release the knock-off lever 87 from engagement with the toothed wheel 95 after the operation of the machine has been arrested. That is to say, after the knock-off lever 87 has been lifted to engage its tailpiece 86 with the rotating wheel 95 and the stopping-mechanism has functioned it is desirable to release the knock-off lever so that it will not be continuously actuated and caused to chatter under the intermittent engagement of the teeth with its end. The slide 35 is slid to the left to slide the pin 80 in the inclined slot 79 in the lever 77 whereby to release the lever 87, this action being more fully explained in the method of operation of the complete machine.

Manually-operable means are provided for releasing the ratchet to return the cone-holder 3 into driving connection with the drive-roll 2 and to concurrently reset the stopping-mechanism to start the winding operation. This manually-controlled means also operates to return the thread-lifter to normal position and the instrumentalities employed for this purpose are illustrated in Fig. 4. They comprise, essentially, a bifurcated frame 100 pivoted on the trunnion-pins 75 which support the thread-lifter 65. Bolted to the depending portions of the

frame 100 is a curved handle or starting-lever 105 which reaches outwardly from the front of the machine in convenient position to be grasped by the operator. Referring to Fig. 4, one end of the frame 100 is extended upwardly in an inclined arm 106 which normally lies adjacent and in alinement with the main portion of the thread-lifter 65. The arm 106 is curled over at the top in an extension 108, see Fig. 4, which is adapted to engage beneath the crooked portion 58 of the detent-rod 56 to rock the latter to engage its detent-blade 60 with the latch-plate 62. The arm 106 of the frame 100 is also provided with a web-like extension 109 which is engaged by the hooked end 110 of the slide 35. It will thus be observed that when the starting-handle 105 is depressed into the position illustrated in Fig. 4 the frame 100 will be rocked to cause its arm 106 to slide 35 to move the dog 43 into position to adapt the quadrant 30 to slide down against the shoe 29 on the dog. During this operation the finger or extension 108 on the arm 106 rocks the detent-rod 56 to engage its blade 60 with the latch-plate 62 and this rocking motion of the rod 56 also operates to rock the lever 52 to release the pawl 50 from the ratchet-teeth on the quadrant 30, the functioning of these parts to start the winding operation being more fully explained hereinafter.

A spring 111 normally holds the frame 100 in the position illustrated in Fig. 1 with its extension 108 bearing against a lug or rest 112 on the bearing-block 18. The spring 111 is connected at 113 to the frame 100 with its opposite end anchored to a pin 114 held in the side of the block 18.

Referring again to Fig. 4, a bell-crank lever 115 is pivoted on the pin 91 which forms the pivotal support for the lever 90 and one of its arms 116 reaches upwardly and is bent over in a finger 117 which engages through a hole 118 in a lug 119 on the frame 100. The lower arm 120 of the lever 115 is adapted to engage the tail-piece 86 of the lever 87 to depress the latter to hold its free end from the teeth on the wheel 95, the lever 115 being rocked to effect this action as shown in Fig. 4 when the starting-lever 105 is depressed to start the winding operation. The method of operation of the complete machine is as follows:

Assuming that the winding has been arrested with the cop- or cone-holder 3 held in raised position above the drive-roll 2 through the means of the ratchet-mechanism shown in Figs. 5 and 6, the machine is prepared for operation by placing a paper shell or tube T on the mandrel or holder. The strand y of yarn or thread is drawn up from its source of supply, not herein shown, and led under the breakage-lever 125, thence across the upper edge of the thread-

lifter 65 and its end secured to the cone-tube T.

With the machine at rest the parts of the stopping-mechanism are in position substantially as shown in Fig. 2. To start the winding the operator grasps the starting-lever 105 and presses it downwardly to the position illustrated in Fig. 4. This action rocks the frame 100 and the latter acts through its connections 109 and 110 on the slide 35 to withdraw the latter until its spring 45 is completely compressed. The slide 35 is thus drawn back into the position shown in Fig. 4 so that the shoe 29 on the dog 43 is moved back to clear the lower end of the quadrant 30.

As soon as the slide 35 has been withdrawn in this manner the further movement of the rocking frame 100 causes its extension 108 to engage the crook or crank 58 at the end of the rod 56 to turn the latter to rock the lever 52 carried at its end. The lever 52 is thus rocked against the tension of its spring 67, see Fig. 6, thereby causing the pin 47 to act against the pawl 50 to release the latter from the teeth 49 on the quadrant 30. Immediately the pawl 50 is released the arm 10 will swing downwardly to lower the cone-holder 3 to bring the surface of the cop-tube carried thereon into contact with the periphery of the continuously rotating drive-roll 2. The contact of the cop-tube with the drive-roll will therefore cause the cop-holder to be rotated therefrom in the direction indicated by the arrow in Fig. 4. As the cone-holder is lowered against the drive-roll 2 the quadrant 30 slides down into position to adapt the shoe 29 on the dog 43 to be frictionally engaged with its convex surface after the slide 35 has been released to allow it to slide rearwardly under the action of its spring 45.

This release of the slide 35 does not take place, however, until the starting-lever 105 has been released by the operator. Previous to this release of the slide 35 the downward movement of the lever 105, and the rocking action of the frame 100 caused thereby, acts through the bell-crank lever 115 to cause the arm 120 of the latter to press the tail 86 of the lever 87 downwardly to remove it from possible contact with the toothed wheel 95. This action of the bell-crank lever 115 thus serves to prevent unwarranted arrest of the winding operation while the strand y of thread or yarn is slack and the breakage-lever 125 dropped so that it will not free the lever 87 or, in other words, lower it away from the toothed wheel 95.

It should be stated that when the thread-lifter 65 is first tilted or rocked upwardly through the action of the lever 90 it is held in this position as shown in Fig. 2 by means of the blade 60 of the detent-rod 56 which slides along the inclined edge 64 of the detent-plate 62 to the position shown in dotted

lines in Fig. 8. In starting the winding operation, therefore, when the starting-handle 105 is depressed to cause the extension 108 on the frame 100 to rock the crank arm 58 of the rod 56 the blade 60 will be slid away from this engagement as last described to allow the thread-lifter 65 to drop into the position shown in Fig. 4 under the action of gravity. At this point the blade 60 on the detent-rod 56 is carried into engagement with the detent-shoulder 61 on the plate 62, see full lines in Fig. 8, and this action causes the stopping-mechanism to be locked in inoperative position. The dropping of the thread-lifter 65 permits the strand *y* of thread or yarn to ride across its upper edge in such relation to the thread-guide 4 that it will be picked up by the guide to seat it in the groove 28 as shown in Fig. 1. This automatic threading of the thread-guide takes place as the guide reciprocates across the path of the thread in the manner as explained in the patent before referred to. As the strand *y* of yarn feeds to the rotating cone-holder or winding-mandrel 3 its slack is taken up and the breakage-lever 125 is suspended thereby to prevent it from influencing the knock-off lever 87 to cause arrest of the winding operation. The operator can now release the starting-lever 105 and the frame 100 will be returned to normal position as shown in Fig. 1 under the action of its spring 111. With the parts of the mechanism set in this relation the winding operation will continue with the thread-guide 4 traversing the strand *y* back and forth longitudinally of the cone-holder 3 to direct it onto the cop-tube T.

When the strand *y* breaks or its supply is exhausted the breakage-lever 125 drops and raises the tail 86 of the knock-off lever 87 into the position shown in Fig. 3 to operate the stopping-mechanism of the machine in the manner as previously explained. Likewise, when the cone reaches a predetermined diameter the stopping-mechanism is released through the disengagement of the quadrant 30 from the shoe 29 on the dog 43 in the manner as next explained. As the quadrant 30 is carried up with the arm 10 its end finally rides off from the shoe 29 to allow the dog 43 to rock on its fixed pivot 42. This permits the rod 35 to slide to the right under the action of its spring 45 as shown in Fig. 3 and the pin 80 at the opposite end of the rod will thereby act through the slot 79 in the lever 77 to rock the elbow-shaped arm 78 of the latter upwardly. The lever 77 is thus caused to act through the crank arm 81 and link 85 to lift the tail 86 of the knock-off lever 87 to bring it into position to be engaged by the teeth on the wheel 95. The rotation of the wheel 95 will therefore cause the knock-off lever 87 to rock the lever 90, thus acting through the tail-piece 93 on

the thread-lifter 65 to tilt the latter upwardly to withdraw the strand *y* of thread or yarn from the thread-guide 4.

As before explained, the raising of the thread-lifter 65 releases the detent-shoulder 61 on the plate 62 from the blade 60 at the end of the rod 56, allowing said rod to be rocked under the action of the spring 67 connected to the lever 52. The rocking of the lever 52 acts through the pawl 50 to force the quadrant 30 upwardly, whereby the arm 10 is raised to lift the cone-holder 3 to remove the cop or cone from contact with the periphery of the drive-roll 2, as shown in Fig. 2. The rotation of the cone-holder 3 is thus arrested and the strand *y* of yarn or thread released from the thread-guide 4 so that the winding operation ceases until the stopping-mechanism is manually operated again in the manner as previously explained. It has been noted that the blade 60 on the rod 56 slides along the beveled edge of the detent-plate 62 to the position shown by dotted lines in Fig. 8 to act as a holding-means to maintain the thread-lifter 65 in raised position until the winding operation is started again, and in this way the machine is maintained inoperative until prepared to wind again.

It has also been explained that after the slide 35 has been moved to the right under the action of its spring 45 to arrest the operation of the machine, the slide is slid back again to tilt the lever 77 downwardly so as to remove the tail 86 on the lever 87 from contact with the stopping-wheel 95. This last action is effected through the operation of the lever 128 on the cam-plate 131 as the rod 56 is rocked by the spring 67, after its blade 60 is released from the shoulder 61 on the detent-plate 62. This last described method of operation of the stopping-mechanism is an improvement over the invention described in the prior application first referred to, in that the removal of the lever 87 from possible contact with the stopping-wheel 95 prevents chatter and jumping of the lever and also eliminates undue strain and wear on the parts.

As another feature of the improvement, the arrangement of the pivoted dogging-member or lever 43 provides for efficient co-action of the dog with the quadrant 30 to insure that the movement of the cop-holder away from the driving-drum shall be properly regulated for the purpose described.

While the present improved controlling-means and stopping-mechanism is herein shown and described as applied to use with a certain type of machine, and as embodied in preferred form or construction, it is to be understood that various modifications may be made in the structure and arrangement of the parts of the device without de-

parting from the spirit or scope of the invention.

Therefore, without limitation in this respect, I claim:

5. 1. In a winding machine, the combination of a rotating winding-mandrel and means for winding strand material thereon, a drive-roll for rotating the cop wound on the mandrel, means adapting the mandrel and drive-roll to separate as the cop increases in diameter, an element slideable by the separation of the mandrel and drive-roll during the growth of the cop, a rockable dog bearing against the slideable element and released therefrom when said element is moved to a predetermined extent, and means operative upon the release of said dog to arrest the operation of the winding machine.
10. 2. In a winding machine, the combination of a rotating drive-roll, a cop-holder for supporting the cop in contact with the drive-roll, means to permit the separation of the cop-holder and drive-roll as the winding increases in diameter, an element slideable by the separation of the cop-holder and drive-roll, a dog pivoted to adapt it to bear against the slideable element and adapted to be released therefrom when the cop reaches a predetermined diameter, resilient means for pressing the dog against said element, and stopping-mechanism operated by the release of the dog to arrest the winding operation.
15. 3. In a winding machine, the combination of a rotating winding-mandrel and means to wind strand material thereon, stopping-mechanism for arresting the rotation of the winding-mandrel, an element having a sliding movement caused by the growth of the package wound on the mandrel, a dog pivoted to rock to bear against the slideable element and adapted to be released therefrom when the slide has been moved to a predetermined extent, resilient means for rocking the dog, and means operative upon the release of the dog from the slideable element to effect the operation of the stopping mechanism.
20. 4. In a winding machine, the combination with a rotatable cop-holder and means to wind strand material thereon, of an element caused to be moved by the growth of the package wound on the cop-holder, a pivoted dog adapted to bear against the movable element, resilient means for holding said dog against said element and acting to move the latter when it is released from said movable element, and stopping-mechanism operated by the release of the dog to arrest the winding operation when the package reaches a predetermined size.
25. 5. In a winding machine, the combination with a rotating cop-holder and means to traverse strand material on the holder,
- of an element caused to be moved by the growth of the package wound on the cop-holder, a fixed support against which the movable element bears, a dog pivoted on said support and having means engaging the opposite side of said element, and means for rocking the dog to cause it to act against the movable element to resist the movement of the latter in the manner and for the purpose substantially as described.
30. 6. In a winding machine, the combination of a rotating drive-roll, a cop-holder on which the cop is wound, a swinging arm for supporting the cop-holder to adapt it to recede from the drive-roll during the growth in the winding, an element connected to said arm to be moved therefrom during the growth in the winding, a fixed support against which said element bears, a dog pivoted on said support and having a shoe bearing on the opposite side of said element, and resilient means for rocking the dog to press its shoe against the element.
35. 7. In a winding machine, the combination of a rotating drive-roll, a cop-holder on which the cop is wound, means adapting the cop-holder to recede from the drive-roll as the cop increases in diameter, an element movable with the cop-holder during the growth in the winding, a fixed pin against which the movable element bears, a dog pivoted on said pin and having a shoe adapted to bear against the opposite side of said element, and resilient means for rocking the dog to cause it to act against the element to frictionally resist the movement of the cop-holder.
40. 8. In a winding machine, the combination of a rotating drive-roll, a swinging arm, a cop-holder supported from said arm to adapt it to recede from the drive-roll as the cop increases in diameter, a quadrant connected to said arm and adapted to be moved therewith during the growth in the winding, a dog pivoted to rock to adapt it to bear against the quadrant, and resilient means for rocking said dog to cause it to act to frictionally resist the movement of the quadrant and thereby the movement of the cop-holder on the swinging arm.
45. 9. In a winding machine, the combination of a rotatable cop-holder, means for traversing strand material on the cop-holder, means for supporting the cop-holder to adapt it to move with respect to the traversing-means as the cop increases in diameter, a quadrant movable with the cop-holder, a fixed support, a dog pivoted on said support and having arms straddling the quadrant and provided with a shoe bearing against one side thereof, and resilient means for rocking the dog to press its shoe against the quadrant.
50. 10. In a winding machine, the combination of a cop-holder, means for traversing

strand material on the cop-holder, means for supporting the cop-holder to adapt it to separate from the traversing-means as the cop increases in diameter, a quadrant movable with the cop-holder, a rockable dog having means adapted to bear against the quadrant to resist its movement, and a slide connected to rock said dog.

11. In a winding machine, the combination of a rotating cop-holder, means for traversing strand material thereon, stopping-mechanism for arresting the rotation of the cop-holder, a knock-off lever connected to operate the stopping-mechanism, a going element for actuating the knock-off lever, automatically-operated means for engaging the knock-off lever with the going element, and means actuated by the operation of the stopping-mechanism to release the knock-off lever from engagement with the going element.

12. In a winding machine, the combination of a rotating cop-holder, stopping-mechanism for arresting the rotation of the cop-holder, detent-means for normally maintaining the stopping-mechanism inoperative, a knock-off lever for releasing the detent-means, a going element for operating the knock-off lever, automatically-operated means for engaging the knock-off lever with the going element, and means operative upon the release of the detent-means to return the automatically-operated means to first position to cause it to release the knock-off lever from the going element.

13. In a winding machine, the combination with the stopping-mechanism thereof, of detent-means for normally maintaining said stopping-mechanism inoperative, a knock-off lever for releasing the detent-means, a going element for operating the knock-off lever, a slide for moving the knock-off lever into engagement with the going element, resilient means for sliding the slide, and means operative upon the release of the detent-means to slide the slide to release the knock-off lever from engagement with the going element.

14. In a winding machine, the combination with a stopping-mechanism thereof, of a rockable member for operating the stopping-mechanism, detent-means for restraining said member from rocking to maintain the stopping-mechanism inoperative, a knock-off lever for releasing the detent-means to permit the member to rock, a going element for operating the knock-off lever, means for moving the knock-off lever into engagement with the going element, and means operated from the rocking member to remove the knock-off lever from engagement with the going element after the operation of the stopping-mechanism.

15. In a winding machine, the combination with the stopping-mechanism thereof,

of a rockable rod, detent-means for locking said rod against rocking action, a knock-off lever for releasing the detent-means, a going element for actuating the knock-off lever, means for moving the knock-off lever into engagement with the going element, a slide for releasing the knock-off lever from engagement with the going element, a cam on said slide, and a lever rockable with the rod to engage the cam to slide the slide in the manner and for the purpose substantially as described.

16. In a winding machine, the combination with the stopping-mechanism thereof, of a rockable member for operating said stopping-mechanism, detent-means for normally restraining said member from rocking, a knock-off lever for releasing the detent-means, a going element adapted to engage the knock-off lever to cause it to act to release the detent-means, a slide for moving the knock-off lever into engagement with the going element, and means operated by the rockable member upon its release from the detent-means to slide the slide to move the knock-off lever out of range of the going element.

In testimony whereof I hereunto affix my signature.
